UNITED STATES PATENT OFFICE.

IRVING WASHINGTON BENEDICT, OF GLOVERSVILLE, NEW YORK.

STALLION-SHIELD.

SPECIFICATION forming part of Letters Patent No. 448,757, dated March 24, 1891.

Application filed June 17, 1890. Serial No. 355,751. (No model.)

To all whom it may concern:

Be it known that I, IRVING WASHINGTON BENEDICT, a citizen of the United States, residing at Gloversville, in the county of Fulton and State of New York, have invented a new and useful Stallion-Shield, of which the following is a specification.

This invention has relation to masturbation-guards for stallions.

- 10 The objects of the invention are to provide an easily applied and removed device adapted to prevent the stallion from exciting his penis by thumping the same against his belly, to construct said device in such a manner as not to interfere with the animal urinating, and which will fold snugly against the belly of the animal when he lies thereupon and afterwards automatically fall to a guarding position when he resumes his feet.
- 20 With the above main and other minor objects in view the invention consists in certain features of construction hereinafter specified, and particularly pointed out in the claims.

25 Referring to the drawings, Figure 1 is a general view of the hind quarters of a horse, a masturbating-guard, constructed in accordance with my invention being applied thereto and in position. Fig. 2 is a detail in perspective of the guard, the view being enlarged. Fig. 3 is a longitudinal section illustrating the different positions the guard may assume.

30 Like numerals of reference indicate like parts in all the figures of the drawings.

35 1 designates a flexible shield, preferably formed of such material as rubber or leather, and in the present instance of the latter-mentioned material. The rear edge of the shield is provided with a central recess 2, leaving at opposite sides of said recess rearwardly-projecting terminals 3. In advance of the terminals the shield is crossed by a surcingle or belly-band 4, adapted to be passed around the body of the stallion and buckled securely 40 in position.

45 5 designates a pair of opposite parallel metal stiffening rods or plates, which are riveted to the shield near its opposite edges and run from the terminals to the front edge of 50 the shield. These rods or plates extend slightly beyond the front edge of the shield, and are bent to form eyes 6. It will be ob-

served that while the rods or plates serve to strengthen and stiffen the shield longitudinally, they do not interfere with the shield 55 bending or yielding laterally so as to conform to the shape and general contour of the animal's belly.

7 designates the masturbating-guard, preferably rectangular and formed of rubber, 60 leather, or any other suitable material, and in this instance of leather. The rear surface of the guard-plate has riveted thereto, as at 8, a semicircular or other shaped metal stiffening frame 9, the two opposite terminals of 65 which extend above the upper edge of the said plate and are bent to form eyes 10, which eyes are at a right angle to the eyes of the metal rods or plates and interlock with the same to form a loose hinge connection. By 70 reason of the loose hinge connection the guard automatically assumes a vertical position, and its forward swing is in this instance limited by a short flexible chain 11, one end of which is connected to the semicircular 75 metal stiffening-frame and the opposite end of which is connected to the under surface of the shield. Other means may be readily devised for limiting the forward movement of the guard, and other forms of hinge connection 80 employed in lieu of the connection herein illustrated.

For the purpose of properly ventilating the surface adjacent to the attachment, I preferably perforate the shield and guard-plate. 85

In applying the attachment, the shield is placed under the belly of the stallion in such position that the sheath of the stallion will take within the recess 2, and the two terminals of the shield will lie at the sides of said 90 sheath, whereby the shield is prevented from any lateral movement. When in this position, it simply remains to connect the ends of the surcingle over the back of the stallion. When the animal is standing, the guard falls 95 by gravity to a vertical position, and when so disposed it is impossible for the stallion to excite his penis by rubbing or thumping the same against his belly. At the same time the device does not in any way interfere with the animal urinating, and no obstruction is offered against which the penis is liable to come when being extended from the sheath for this purpose. When the animal lies down so that 100

his belly is in contact with the ground, the guard folds upward and to the rear and folds up flatly in position and out of the way, thus not discomfiting the animal or becoming 5 broken by his weight thereupon.

Having thus described my invention, what I claim is—

1. In an appliance to prevent masturbation in stallions, a shield and means for attaching 10 the same under the belly of the animal, said shield being provided with a depending guard adapted to fold up under the shield, substantially as specified.
2. In an appliance to prevent masturbation

in stallions, the belly-shield and means of attaching the same to the animal, the shield being provided at its front edge with a pair of eyes, and the guard-plate provided at its upper edge with similar eyes for interlocking with those of the shield, substantially as specified. 15 20

In testimony that I claim the foregoing as my own I have hereto affixed my signature in presence of two witnesses.

IRVING WASHINGTON BENEDICT.
